The ornamental design for a newspaper vending machine, substantially as shown and described.

DESCRIPTION

FIG. 1 is a top front and left side perspective view of a newspaper vending machine, showing my new design; FIG. 2 is a front elevational view thereof;

FIG. 3 is a side elevational view thereof, the opposite side being a mirror image thereof;

FIG. 4 is a rear elevational view thereof; and

FIG. 5 is a bottom plan view thereof.
